UNITED STATES PATENT OFFICE.

PETER WILSON, OF SPRINGFIELD, ILLINOIS.

SAFETY DEVICE FOR ELEVATORS.

Application filed August 20, 1923. Serial No. 658,339.

To all whom it may concern:

Be it known that I, PETER WILSON, a citizen of the United States, residing at Springfield, county of Sangamon, and State 5 of Illinois, have invented a Safety Device for Elevators, of which the following is a specification.

This invention relates to safety appliances commonly used in connection with lift elevators, such as passenger elevators used in 10 office buildings and the like, or in connection with cages used for hoisting coal, etc.

The purposes of this invention are; First, to provide an economical and simple means 15 of providing protection for lift elevators that will be reliable and really safe.

A further object of my invention is to provide a device for the purpose mentioned that will be easy to keep in repair and easily 20 and quickly repaired when occasion demands it.

A further object of my invention is to provide a device of the character hereinabove mentioned that is adapted to work in all 25 cases without fail.

The particular merit in my invention is to be found in its simple and easy operation, using the very simplest means possible for getting the most needed and unfailing 30 action in cases of emergency in the event of an elevator cable breaking.

The desired objects of my invention are obtained by the safety device for elevators described in the annexed specification recited 35 in the claims and illustrated in the accompanying drawing in which like reference numerals indicate the same structural parts in the several figures.

Fig. 1 is a perspective view of the assembled parts of the safety device of my 40 invention.

Fig. 2 is a perspective view of a section of the guide rail adapted to act as a guide for the elevator device of my invention.

Fig. 3 is a perspective of the counter-weighted dog adapted to mesh with stop-lugs 3 on the vertical guide rail shown in Fig. 2.

Fig. 4 is a perspective of the counter-weight which is adapted to assist in dropping grappling dog 2 into meshing relation with stop-lugs 3 shown in Fig. 2 in the event of sudden parting of cable supporting an elevator.

Fig. 5 is an end view of the device of my invention in part showing the normally rela-

tive position of the grappling dogs both when in meshing engagement and when out of it. This figure also shows the shapes of the stop-lugs and a section of the steel beam 60 on which the device of my invention is mounted.

Fig. 6 is a side view of the device of my invention in part showing the relative position of the grappling dogs and the stop-lugs with which it meshes.

Fig. 7 is a top view in part of the device of my invention showing how the grappling dogs are mounted on the steel beam of the elevator and showing also in the meantime the relative position of said grappling dogs with respect to the vertical alignment 70 of the perpendicular guide rail which not only serves as a guide for elevator but also carries integral therewith the stop-lugs or 75 cogs of the particular design shown which serve as stop means for the elevator when in the event of the suspending cable breaking the grappling dogs automatically drop into a quick meshing engagement with said 80 rack.

The preferred embodiment of my invention is illustrated in the several figures above mentioned and the desired means of operating this device will be clearly understood 85 by carefully observing the illustrations when reading the instructions concerning the operation of this device.

A detailed description therefore of this device will be noted as follows: When it 90 is desired to install the device of my invention on a lift elevator perspective drawing shown in Fig. 1 will illustrate the relative position of the several parts thereof. For instance, when it is desired to assemble the several parts the engineer will proceed as follows: First, attach brackets 24, three pairs of the same in corresponding relative positions on each of the two sides of the beam of the elevator. These will be attached of course to the vertical plane of the beam as shown. It will be noted that there is one grappling dog on each side of each vertical guide rail which carries the meshing stop-lugs with which said grappling dogs are adapted to mesh on corresponding opposite sides. It will be also noted that there is on the same shaft alignment with said grappling dogs a counterweight in the middle of the space between the two end dogs 100 that are found on the same side of the elevator beam. It is to be here noted that said 105

counterweight is adapted to be suspended from the same supporting ring on which the elevator is supported which ring is attached directly to the cable which supports the elevator.

Character 28 Fig. 4 is a keyed tubular sleeve integral with auxiliary counter-weight —6— and adapted to hold said counter-weight in a centrally disposed location on the counter-shaft on which it is supported.

It will be observed that as long as the elevator cable is in good shape the grappling dogs and the counterweights are simultaneously lifted to a rotatively elevated position in which they are held as long as the elevator is being supported by the cable, but in the event of the elevator cable breaking said grappling dog will quickly rotatively drop to an engaging position with rack lugs 3 on vertical guide rail made integral therewith.

Referring now to the detail parts of the device, numeral 1 is the base of the vertical guide rail which acts as a guide means for an elevator. Numeral 2 is the grappling cogs of the dogs adapted to mesh with the lugs of rack 3 on the vertical guide rail. Numeral 3 shows the lugs of the rack with which grappling dogs mesh in an emergency. Numeral 4 is the hole in the grappling dog through which horizontal shafts 7 and 8 pass in mounting said dog into normally operating position. Numeral 5 is the counterweight made integral with said grappling dogs. Numeral 6 is also a counterweight made integral with said counterbalance which is adapted to aid in dropping said grappling dogs into meshing engagement with the stop-lugs in emergency. Numerals 7 and 8 illustrate the corresponding horizontal oppositely mounted shafts which are supported by brackets 24 which shafts are adapted to serve as supporting means and pivot means for rotatively mounted grappling dogs and center mounted counterweight. Numeral 9 indicates the part of the vertical guide rail which is adapted to come in contact with the guide elements of an elevator. Numerals 10 and 11 and 11' are detail parts of the elevator beam on which the device of my invention is mounted. Numeral 12 is the vertical plate running up and down a shaft serving as supporting means for vertical guide rail above mentioned. Numeral 13 is the partition or walling means for walling up the shaft. Numeral 14 is the bottom plate of the beam structure of the elevator. Numeral 15 is the eye bolt serving as attaching means for the suspending elevator cable. Numeral 16 indicates the position of the rectangular hole in the elevator beam plate through which the meshing cogs of said grappling dogs are adapted to pass when moving into meshing

engagement with said vertical stop-lugs. Numeral 17 indicates the flank portion of said vertical guide rail. Numeral 18 indicates the elevator supporting cable. Numeral 19 indicates the ring from which is suspended the several attaching cables which radiate therefrom and attach to the eye bolts of the elevator by which means the elevator is suspended. Numerals 20 and 21 indicate said attaching cables. Numerals 22 and 23 are correspondingly opposite supporting cables for the rotatively mounted counterweights and grappling dogs of the device of my invention. It is to be noted that these two corresponding supporting cables just mentioned are also centrally attached at their upper ends to the same ring to which the diverging elevator supporting cables are attached. Numeral 24 indicates the bracket which is adapted to support horizontal shafts 7 and 8 on which are mounted the grappling dogs and counterweights above mentioned. Numeral 25 indicates the elevator frame work. Numeral 26 indicates the attaching means for connecting the frame work of the elevator to the supporting beam thereof. Numeral 27 indicates the floor of the elevator.

It will be noted in the detail study of the details of my invention that certain minor details in the construction of my invention may be varied in design and still stay within the spirit and scope of my invention.

Having thus described the nature of my invention what I claim as new and useful and desire to secure by Letters Patent is—

1. In a safety device for elevators the combination comprising a pair of opposite vertical shaft guides for the elevator; each having a plurality of vertically aligned stop-lugs, an elevator beam adapted to be guided by said vertical guides in the vertical movable support of the elevator, parallel opposite horizontal supporting shafts rotatably mounted through supporting counter shaft brackets; emergency catch dogs in opposite pairs secured to the ends thereof, and adapted to rotate with said rotatable counter-shaft; auxiliary mounted counter weights secured to and centrally disposed on said rotatable counter shafts and adapted to simultaneously rotate with said rotatable counter shafts by action of gravity in the rotating movement thereof in bringing said emergency catch dogs into emergency engagement with said stop lugs in said elevator guides in the event of accidental parting of the elevator supporting cable.

2. An elevator safety device of the character described comprising a pair of opposite vertical shaft guides for the elevator provided with integral vertical stop-lugs, an elevator supporting beam provided with oppositely positioned counter shaft supporting

- brackets, a pair of horizontal parallel rotatable counter shafts rotatably mounted in said brackets; oppositely mounted rotatable counter-weighted emergency catch dogs 5 adapted to normally engage with said vertically aligned stop-lugs by the action of gravitation in the event of an accidental parting of the supporting cable for the elevator; auxiliary centrally disposed counter 10 weights securely mounted on said counter shafts and adapted to aid in expediting the emergency rotation of said emergency catch dogs as described and for the purpose set forth.
- 15 3. In an elevator safety device of the character described, the combination with, vertical guide members in the elevator shaft, having integral vertically aligned stop-lugs on opposite side faces thereof, of a cage having opposite sets of counter-balanced emergency catch dogs mounted on bracket supported horizontally parallel opposite counter
- shafts, adapted to provide simultaneous rotatable support of said catch dogs; said rotatably supported emergency catch dogs 25 adapted to be normally suspended in a predetermined position of disengagement with the integral vertically aligned stop-lugs during the cable support of said elevator; but adapted to quickly and automatically 30 rotate simultaneously into engagement with said stop-lugs through the agency of gravitation on said rotatable counter weighted grabbing dogs in the event of accidental breaking of the elevator supporting cable; and an auxiliary centrally disposed pair of counter weights securely mounted on said counter shafts and adapted to aid in expediting the emergency rotation of said 35 emergency catch dogs as described and for the purpose set forth.
- 40

In witness whereof I hereunto set my hand and seal this 13th day of August A. D. 1923.

PETER WILSON. [L. s.]
